METHOD OF AND MEANS FOR MAKING
WEATHERPROOF NAILS

Robert B. Dickson, Evanston, Ill., assignor to
Dickson Weatherproof Nail Company, Evans-
ton, Ill., a corporation of Delaware

Application March 2, 1940, Serial No. 321,970

5 Claims. (Cl. 10—156)

This invention relates to improvements in method of and means for making weatherproof nails and it consists of the matters hereinafter described and more particularly pointed out in the appended claims.

The weatherproof nail with which the present invention is more especially concerned is one wherein the head is enclosed in a cap of softer metal, with a part of the cap surrounding an adjacent portion of the shank.

One of the objects of the present invention is to provide a method of producing a weatherproof nail of this kind which does not require the provision of a specially formed head on the nail blank.

Also, it is an object of the invention to provide a method whereby the cap may be applied to the head of an ordinary wire nail in a manner to enclose the entire head and to surround a portion of the shank near said head with cap material so as to provide a better seal for the head when driven through sheet metal.

Another object of the invention is to provide a method of making nails of this kind that insures uniformity in the finished nails and by which method the operations may be performed rapidly so that cost of production is relatively low.

A further object of the invention is to provide simple and efficient means whereby the improved method may be carried out.

The above mentioned objects of the invention, as well as others, together with the several advantages thereof will more fully appear as the specification proceeds.

In the drawing:

Fig. 1 is a perspective view of a weatherproof nail made in accordance with the improved method.

Fig. 2 is a vertical sectional view through associated die members of one form of means for carrying out the improved method, and shows the said die members in their normal relative positions for supporting the nail in a position with the head of the nail spaced above the bottom of the cavity in one die member and with a mass of softer cap metal engaged upon the top surface of the nail head.

Fig. 3 is a view similar to Fig. 2 and illustrates that step of the method wherein the mass of metal has been subjected to an initial pressure which changes its shape and displaces a portion of said metal about the top of said head of the nail; its periphery and the outer marginal parts

of the underside of the nail head to form a partially completed cap thereon.

Fig. 4 is a view similar to Fig. 3 and illustrates that step of the method after the die members have been separated axially and whereby the inner marginal portion of the underside of the nail head and the adjacent portion of the shank have been uncovered.

Fig. 5 is a view similar to Fig. 4 and illustrates that step of the method wherein the partially completed cap is subjected to final pressure to displace a portion thereof inwardly toward the shank to cover the uncovered inner marginal portion of the underside of the nail head as well as to surround the adjacent portion of the shank.

Referring now in detail to the weatherproof nail shown in Fig. 1 and produced by the improved method, the same comprises a conventional or "stock" wire nail 10 and a weatherproof cap 11 of a metal softer than that of the nail. Lead is a metal which is much softer than the metal of the nail and which is well adapted for capping purposes. The nail includes a shank 12 having a driving point 13 at one end and a round substantially flat head 14 at the other end. The underside 15 of the head flares upwardly and outwardly from the shank to the peripheral edge of the head.

The cap 11 as here shown, includes a crowned top wall or portion 16 enclosing the top of the nail head and a peripheral portion 17 surrounding the periphery of the nail head and terminating at the bottom in an annular sealing flange 18. Said cap further includes a bottom portion 19 enclosing the flared bottom or underside of the nail head and a collar or ferrule 20 that surrounds that portion or neck of the shank adjacent the head.

40 The means shown in Figs. 2 to 5 inclusive include a die member 21 having an axially disposed cavity 22 that opens through the top end of the die member. The cavity 22 is of a diameter somewhat larger than that of the nail head as best shown in Fig. 2. The bottom of the cavity is indicated at 23 and a part of said bottom is defined by an annular groove 24. The die member 21 is fixed in a support or holder 25 having upper and lower bore portions 26 and 27 respectively of different diameters and meeting as an annular shoulder 28. The upper bore portion 26 is of a diameter larger than lower bore portion 27 and snugly receives the die member 21 which engages at its bottom margin on said shoulder. The bottom 23 of said die member 21 has an axial bore

29 therein of a diameter smaller than that of the cavity.

The upper end of a relatively heavy thimble 30 is disposed in the support or holder 25 for a movement toward and away from the die member 21. The thimble has lower and upper bore portions 31 and 32 respectively, the lower bore portion having a diameter greater than the upper bore portion which is the same as that of the bore portion 29 in the die member 21. A ferrule or sleeve 33 is fixed in the bore portion 32 and said sleeve is of such length that when the top end of the thimble engages the bottom of the die member 21, the top end of the ferrule projects a suitable distance above the bottom 23 of the die cavity to form a nail head engageable shoulder 34. The ferrule is secured in the top end of the thimble by a set screw 35. If desired the shoulder 34 may be formed as an integral part of the thimble. However, as said shoulder is subject to wear, it is preferred that the same be made in the manner before described as this permits the replacement of the ferrule, when said shoulder is worn, instead of requiring the replacement of the entire thimble. The ferrule has an inside diameter or bore 33a which is somewhat larger than the diameter of the nail shank it receives so as normally to leave a small annular clearance space between the nail shank and the ferrule. The inner upper end corner of the ferrule is rounded as best appears in Fig. 2.

In carrying out the method by means of the structure shown in Figs. 2 to 5 inclusive the procedure is as follows: The shank 12 of a nail is inserted point first into the die cavity so as to pass through the ferrule 33 until the nail head 14 engages on the shoulder 34. Thereafter a mass of lead 11x (see Fig. 2) is placed upon the top of the nail head. A punch 36 is then caused to enter the cavity 22 from its open top end to engage the mass 11x. The punch is then forced toward the bottom 23 of the cavity 22, reforming the mass and causing displacement of a part thereof so as to flow around the periphery to engage the bottom 23 of the cavity and to fill up the groove 24. Furthermore, a part of said mass is displaced to flow inwardly and enclose the outer marginal portion of the underside 15 of the nail head and into substantial engagement with the outer surface of that top end part of the ferrule, above said bottom 23. Thus a partially completed cap is formed about the nail head with the parts as arranged in Fig. 3.

A relative axial movement is then produced between the die member 21 and thimble 30 so that the top end of the ferrule 33 which forms the shoulder 34 is disposed substantially flush with the bottom 23. In this position of the parts which appears in Fig. 4, an annular space 37 is formed about the shank near the head which uncovers the inner marginal portion of the underside of said nail head and the adjacent portion of the nail shank. The plunger 36 is then caused to move further toward the bottom 23 of the cavity with a heavy displacing pressure which causes parts of the uncompleted cap to flow inwardly to form the bottom 19 of the cap. In this movement of the punch, a part of the excess metal flows down in the top end of the space between the top end of the ferrule 33 and adjacent part of the nail shank 12 to form the collar 20. This produces the finished capped nail. Thereafter the plunger 36 is withdrawn from the cavity 22 and the capped nail is then

ejected from the cavity 22 by some means that engages the bottom portion of the shank. The finished capped nail appears in Fig. 1.

By the method and means described, it is possible to apply a cap to an ordinary wire nail and which cap completely covers the entire underside of the head of the nail as well as to surround that portion of the shank of the nail near its head. Therefore it is not necessary to employ a specially shouldered nail for producing a capped nail of this kind, as heretofore has been the practice.

While in describing the invention I have referred in detail to the steps of the method as well as to the sequence thereof along with structure whereby said method may be carried out, the same is to be considered only in the illustrative sense so that I do not wish to be limited thereto except as may be specifically set forth in the appended claims.

I claim as my invention:

1. The method of making a weatherproof nail which consists in disposing a nail in operative position in the cavity of a die having a part extending upwardly from the bottom of said cavity to surround a part of the shank of the nail near its head and to engage the inner marginal part of the said head so as to support the nail in the die with its head disposed above said cavity bottom and to cover said part of said head and said shank respectively, placing a mass of softer cap metal in said cavity so as to engage upon said head, applying a pressure to said mass so that it is deformed out of its original shape, and a part of said cap material is displaced over the top of the nail head about its periphery and then toward and into engagement with the bottom of said cavity as well as into engagement with the outer marginal part of the underside of said head and into engagement with said part extending upwardly from the bottom of said cavity, moving said first mentioned part away from the head of the nail so as to uncover said inner marginal part of the underside of the nail head as well as the first mentioned part of the shank and whereby the nail is supported in the cavity by said partially completed cap, and then applying a further pressure to the partially completed cap to cause a displacement of a portion thereof inwardly toward the shank so as to cover the uncovered inner marginal part of the underside of the head and to surround the uncovered part of said shank.

2. Means for making weatherproof nails embodying therein a die member having a cavity therein, means disposed axially of said die member for receiving the shank of a headed nail when the same is inserted into said cavity, said means carrying a portion that normally projects above the bottom of said cavity so as to be engaged by a part of the underside of the head of said nail so as to support the same in a position above the bottom of said cavity, said die member and said means being relatively movable axially so as to change the relative position between the top edge of said portion of said means and the bottom of said cavity.

3. Means for making weatherproof nails embodying therein a die member having a cavity therein, means disposed axially of said die member for receiving the shank of a headed nail when the same is inserted into said cavity, said means carrying a portion that normally projects above the bottom of the cavity so as to be engaged by a part of the underside of said head of the nail so as to support the same in a position

tion above the bottom of said cavity, said means being disposed for movement away from and toward the die member so as to change the relative position between the top edge of said portion of said means and the bottom of said die cavity.

4. Means for making weatherproof nails embodying therein a die member having a die cavity therein, means disposed axially of said die member for receiving the shank of a headed nail when the same is inserted into said cavity, means providing a ferrule detachably secured to said means and having an end that normally projects above the bottom of said die cavity to provide a top edge part adapted to be engaged by a part of the underside of the head of said nail so as to support the same in a position above the bottom of said cavity, said die member and said means being relatively movable axially so as to change the relative position between said top edge part and the bottom of said cavity. 20

5. Means for making weatherproof nails embodying therein a die member having a cavity therein, a support in which said die member is fixed against at least axial movement, means in said support axially of said die member for receiving the shank of a headed nail when the same is inserted into said cavity, a ferrule detachably secured to said means and having an end that normally projects above the bottom of said die cavity to provide a top edge part adapted to be engaged by a part of the underside of the head of said nail so as to support the same in a position above the bottom of said cavity, said means being disposed in said support for movement away from and toward the die member so as to change the relative position between said top edge part and the bottom of said cavity.

ROBERT B. DICKSON.
